FIG. 2

INVENTOR

Reginald H. Waters.

UNITED STATES PATENT OFFICE.

REGINALD H. WATERS, OF CUMBERLAND, MARYLAND, ASSIGNOR TO KELLY-SPRING-FIELD TIRE COMPANY, OF NEW YORK, N. Y., A CORPORATION OF NEW JERSEY.

DESIGN FOR A VEHICLE-TIRE.

59,310.

Specification for Design.

Patented Oct. 4, 1921.

Application filed June 2, 1921. Serial No. 474,578. Term of patent 14 years.

To all whom it may concern:

Be it known that I, REGINALD H. WATERS, a citizen of the United States, residing at Cumberland, county of Allegany, and State of Maryland, have invented a new, original, and ornamental Design for a Vehicle-Tire, of which the following is a specification, reference being had to the accompanying drawing, forming a part thereof.

Figure 1 is a partially complete perspective view of a tire, showing my new design. "A" designates a series of opposed notches

radial of the tire, in spaced and staggered relation, each notch terminating in open communication with an annular groove "B."

Fig. 2 is a cross-sectional view through the line 2—2 of Fig. 1.

I claim:

The ornamental design for a vehicle tire, as shown and described.

Signed at Cumberland, in the county of Allegany, in the State of Maryland, this 1st day of June, 1921.

REGINALD H. WATERS.
